United States Patent Office

Des. 213,558
Patented Mar. 18, 1969

213,558

BASIN

Richard C. Colborn, % Cultured Marble Products, 1241
E. Main St., Santa Paula, Calif. 93060

Filed Apr. 7, 1967, Ser. No. 6,587

Term of patent 14 years

U.S. Cl. D23—58
Int. Cl. D23—02

1.
2.
3.

FIG. 2.

FIG. 3.

FIG. 1 is a perspective view of a basin showing my new design;

FIG. 2 is a top plan view thereof; and,

FIG. 3 is a front elevational view thereof.

The ends of the design being broken away to indicate indefinite length.

The broken line representation of a faucet and its handles in FIG. 1 are for purposes of illustration only.

I claim:

The ornamental design for a basin, as shown and described.
